UNITED STATES PATENT OFFICE.

ORRELL ASHTON, DECEASED, LATE OF SWAMPSOTT, MASSACHUSETTS, BY HANNAH ASHTON, EXECUTRIX, OF SWAMPSOTT, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

APPARATUS FOR USE IN ASSEMBLING SOLES ON LASTS.

1,312,509.

Specification of Letters Patent. Patented Aug. 12, 1919.

Application filed February 15, 1916. Serial No. 78,521.

To all whom it may concern:

Be it known that ORRELL ASHTON, deceased, late of Swampsott, in the county of Essex and State of Massachusetts, invented 5 certain Improvements in Apparatus for Use in Assembling Soles on Lasts, of which the following description, in connection with the accompanying drawings, is a specification, like reference characters on the drawings 10 indicating like parts in the several figures.

This invention relates to the manufacture of shoes and more particularly to means for securing greater accuracy and effecting economy in shoemaking. The soles of good 15 turn shoes consist of high-grade leather of the most expensive quality. One object of this invention is to provide means to assist an operative in placing a sole on a last, preparatory to assembling the upper therewith, 20 with its edge in proper symmetrical relation to the edge of the last so that the shoe can be correctly shaped over the sole. Another object is to insure the placing of the sole on the last so that a minimum of sole edge 25 trimming shall have to be done and therefore a minimum of waste of valuable stock shall occur in finishing the shoe.

A feature of the invention consists in means constructed and arranged to engage 30 the work at a plurality of points for positioning a sole symmetrically relatively to an end of a last. The illustrative embodiment of the invention comprises feelers with which the last and the sole may be brought into engagement at opposite sides of the end of the toe, and also at the end of the toe. These 35 feelers comprise relatively adjustable members for engaging, respectively, the side face of the last and the edge of the sole to adapt 40 the apparatus for turn shoe work, the sole edge member determining the extent of projection of the sole edge beyond the edge of the last. With each feeler is also preferably 45 associated a finger to engage with the top face of the sole to assist the operator in using the apparatus.

Another feature of the invention consists in the organization of the apparatus for adjustment of a plurality of feelers together. 50 As shown, opposed side feelers, which are arranged for engagement with the work at the corners of the toe, and an intermediate feeler, which is located to engage the end of

the toe, are mounted on relatively movable supports which are connected for movement of two feelers together for adaptation to the size of the work. A spring is arranged to hold the feelers in a normal position from which they may be spread by engagement with the work; and, for alternative use, a 60 binding screw is arranged to secure the feelers in definite adjusted relation. 55

A further feature of the invention consists in the combination with sole locating means of means coöperating therewith to secure 65 the sole in the correct location on the last.

The invention will be more fully explained in connection with the accompanying drawings and will then be pointed out 70 in the claims.

In the drawings,

Figure 1 is a side elevation showing this invention applied to an insole tacking machine.

Fig. 2 is a perspective view of the new 75 mechanism, and

Fig. 3 is a sectional view illustrating a use of the invention.

The illustrative apparatus comprises a standard 1 which may be supported by a bracket extending laterally from the post of a tacking machine such as that shown in United States Letters Patent No. 1,106,393, granted Aug. 11, 1914, on application of Fred L. Mackenzie. The head of the standard consists of longitudinal and transverse arms 2, 3, 4 and 5. The longitudinal arms 3 and 5 contain a guideway in which is slidingly mounted a bar 6 the front end of which constitutes the last engaging member of the toe end feeler. Upon the front end of the bar 6 is located a block 8 which constitutes the sole edge engaging member of that feeler. The last engaging member 6 and the sole engaging member 8 are each tapered to narrow bearing faces at their work engaging ends. The block has a longitudinal slot and is confined in adjusted position by a binding screw 10 and a cap plate 12 which has depending flanges embracing the block and the 80 bar 6 and the forward end of which is extended to form fingers that overlie and engage the margin of the sole. 85

The transverse arms 2 and 4 pivotally support angle levers 16 the front arms of 105 which are bent inwardly to engage the cor-

ners of the toe substantially normal to its curvature at those points, said arms constituting the last engaging members of the corner feelers. These feelers are constructed like the toe end feeler above described.

The other arms of the angle levers 16 are overlapped at their ends, the upper one being provided with a slot through which extends upwardly a stud 18 carried by the lower arm. A tension spring 20 extends from stud 18 backwardly to a stud 22 in the rear end of the bar 6 and is adapted to hold the three feelers in normal proximity. The lower end of stud 22 depends below bar 6 and acts as a stop to limit forward movement of that bar.

One of the levers 16 has an arcuate slot through which a binding screw 25 extends and is threaded into the arm 4 of the machine head. This binding screw can be used if desired to hold the side feelers in any desired relation, the end feeler and the slide 6 being free to yield backwardly against the resistance of the spring 20.

In a use which I have advantageously made of the apparatus, the sole edge engaging members 8 are adjusted relatively to the last engaging members 6 and 16 to provide for the desired projection of the sole beyond the edge of the last, as indicated in Figs. 2 and 3, and are secured in adjusted position by the binding screws 10, and the binding screw 25 is left loose. The apparatus is attached to an insole tacking machine in such position that it can be engaged by a shoe presented to the nozzle 30 of the tacker, and the operative takes a last and a turn shoe sole in his hands, places the sole with its toe end extending beyond the toe end of the last farther than the normal projection and thrusts the work into the feelers, being guided as to vertical position by the fingers 12. As the work engages the feelers they center the toe of the sole on the last and push it back to where it presents the normal projection beyond the edge of the last for which blocks 8 are set. With the work in this position at the toe the operative positions the heel end of the sole on the heel of the last and then presents the shoe to the nozzle 30 of the insole tacker from which a tack is driven by driver 32 into the forepart of the sole for securing the sole in adjusted position upon the last bottom. The shoe is then shifted and a second tack driven into the shank to secure the rear part of the sole in position. Instead of combining the sole locating apparatus with a tacking machine as above described so that the apparatus can position and hold the sole while the tacker fastens it, many of the advantages of this invention may be obtained by locating the apparatus more remote from the tacker where the operative will first present the work to said apparatus and then transfer

the work to tacking position while holding the sole in proper location on the last. Alternatively the last may be supported in operative relation to the sole locating apparatus and the tacking performed by hand.

Having explained the nature of the invention and described how it may be embodied in useful form and employed, I claim as new and desire to secure by Letters Patent of the United States:—

1. An apparatus for use in assembling soles on lasts having, in combination, a last engaging member, a superposed sole edge engaging member, a sole margin engaging member, and means for securing the last engaging member and the sole edge engaging member in relation to locate a sole so that it will project a predetermined distance outside of the edge of the last.

2. An apparatus for use in assembling soles on lasts having, in combination, a last engaging member, a superposed sole edge engaging member, a sole margin engaging member, means for securing the last engaging member and the sole edge engaging member in relation to locate a sole relatively to the edge of the last, and means to fasten the sole to the last while the sole is in engagement with said means.

3. An apparatus for use in assembling soles on lasts having, in combination, means presenting three bearing faces to engage a last around the toe, means carried by said first named means presenting three bearing faces to engage a sole edge around the toe and to position the sole relatively to the last, and means for securing said sole and last engaging means together in relatively adjusted positions to permit a predetermined projection of the sole beyond the edge of the last at three points.

4. An apparatus for use in assembling soles on lasts comprising a feeler having a member to engage the side face of a last locally at substantially a point, and carrying a member located above the last engaging member and back from its edge to engage the edge face of a sole projecting outside the edge of the last, and a member overlying the sole edge engaging member and extending forwardly beyond the last engaging member to project over the margin of the sole, said member being provided with a sight opening to reveal to the operator the location of the sole edge relatively to the sole edge engaging member.

5. An apparatus for use in assembling soles on lasts comprising a carrier, three yielding feelers thereon arranged to engage the end and the two corners of the toe at points spaced apart, each feeler having a last side engaging face and a sole edge engaging face, and means for securing the sole and last together.

6. An apparatus for use in assembling

- soles on lasts comprising a carrier, three yielding feelers thereon arranged to engage the end and the two corners of the toe at points spaced apart, each feeler having a 5 last side engaging face and a sole edge engaging face which are relatively adjustable to secure different relations of the edges of the sole and the last, and a tacker disposed in relation to the shoe to insert a tack 10 through the sole into the last. 70
7. An apparatus for use in assembling soles on lasts comprising a carrier and three feelers thereon arranged to engage the end and the two corners of the toe at points 15 spaced apart, movable connections between the feelers and the carrier, and means holding said feelers normally toward each other and permitting relative yielding movement of the feelers by a last and sole thrust between them to adapt them to act on toes of 20 different widths upon manual presentation of the shoe by the operator. 80
8. An apparatus for use in assembling soles on lasts comprising three feelers arranged to engage a toe at its end and opposite corners and mounted for movement in directions approximately normal to the contacting surfaces, and means yieldingly holding the feelers toward each other and permitting them to move for adaptation to 25 widths of toes upon manual presentation of a shoe by the operator. 90
9. An apparatus for use in assembling soles on lasts comprising sole tacking means, three feelers arranged to engage a toe at its end and opposite corners and mounted for movement in directions approximately normal to the contacting surfaces, and means yieldingly holding the feelers toward each 30 other and permitting them to move for adaptation to widths of toes, each feeler comprising a last side engaging member and a sole edge engaging member the acting face of which is located back of the acting face 35 of the last engaging member to allow the sole to project outside the last. 100
10. An apparatus for use in assembling soles on lasts comprising devices each arranged for engagement by the toe of a sole 40 and the toe of a last, said devices acting at a plurality of points including points located at opposite sides of the toe to center a sole toe on the toe portion of the last as the work supported in the hands of the operator is 45 thrust into contact with the devices. 105
11. An apparatus for use in assembling soles on lasts comprising devices arranged for engagement by the toe of a sole and the toe of a last, said devices acting at a plurality of points including points located at 50 opposite sides of the toe to center a sole toe on the toe portion of the last as the work supported in the hands of the operator is thrust 55 into contact with the devices, the sole engaging devices located at the opposite sides of 110
- the toe being constructed and arranged for independent adjustment to permit a predetermined projection of the sole beyond the edge of the last bottom at each corner of the toe. 70
12. An apparatus for use in assembling soles on lasts comprising a carrier, angle levers fulcrumed at opposite lateral sides of the carrier and having overlapping inwardly extending arms and forwardly extending 75 arms, feelers mounted on the forward arms to engage a toe and center a sole on a last, a pin and slot connection between the inner arms, and a spring holding the angle levers in a normal position relatively. 80
13. An apparatus for use in assembling soles on lasts comprising a carrier, angle levers fulcrumed at opposite lateral sides of the carrier and having inwardly extending arms and forwardly extending arms, feelers 85 mounted on the latter arms to engage a toe and center a sole on a last, and means acting through the inner arms of the levers to determine the spread of the feelers. 14. An apparatus for use in assembling soles on lasts comprising a carrier, angle levers fulcrumed at opposite lateral sides of the carrier and having inwardly extending arms and forwardly extending arms, feelers 90 mounted on the latter arms to engage a toe and center a sole on a last, a slide movable longitudinally between the levers and having a feeler to engage the toe end of the work, and means to hold the feelers in proximity and allow separation for widths of 95 toes. 100
15. An apparatus for use in assembling soles on lasts comprising a carrier, angle levers fulcrumed at opposite lateral sides of the carrier and having inwardly extending arms and forwardly extending arms, feelers 105 mounted on the latter arms to engage a toe and center a sole on a last, a slide movable longitudinally between the levers and having a feeler to engage the toe end of the work, and means for securing the angle levers with the feelers carried by them in 110 definite relation. 16. An apparatus for use in assembling soles on lasts comprising a carrier, angle levers fulcrumed at opposite lateral sides of the carrier and having inwardly extending arms and forwardly extending arms, feelers 115 mounted on the latter arms to engage a toe and center a sole on a last, a slide movable longitudinally between the levers and having a feeler to engage the toe end of the work, means for securing the angle levers with the feelers carried by them in definite relation, and a spring for holding the slide forwardly 120 under pressure of a toe thrust between the side feelers. 17. An apparatus for use in assembling soles on lasts comprising yielding devices ar- 125 130

14
ranged for engagement by a toe at a plurality of points including points located at opposite sides of the toe to center a sole toe on the toe portion of the last as the work is 5 thrust between the devices, a similar yielding device to engage the end of the last and determine the projection of the sole at the end of the last, and means arranged with relation to said devices for fastening the sole to 10 the last while it is so centered.

18. An apparatus for use in assembling soles on shoes, having sole centering means

comprising devices constructed and arranged to engage the upper and the sole of a shoe at points on opposite sides of the toe and to 15 engage the toe end of the shoe upper and sole, together with means including a single spring constructed and arranged to impart a yielding quality to said devices.

In testimony whereof I have signed my 20 name to this specification.

HANNAH ASHTON,
Executrix of the will of Orrell Ashton, deceased.
